STRIPER

Jerome E. Doss, Tampa, Fla.

Application February 8, 1941, Serial No. 378,086

6 Claims. (Cl. 91—62.5)

The present invention relates to new and useful improvements in stripers and more particularly to stripers such as are employed for painting stripes on automobile bodies and various other structures.

An important object of the invention is to provide a stiper which employs one or more paint-applying elements in an interchangeable manner.

Still another important object of the invention is to provide a stiper constructed in such a manner as to permit the applying of stripes in various colors.

A further object of the invention is to provide a stiper assembly employing a guide which can be adjusted in an easy and convenient manner.

These and other important objects and advantages of the invention will become apparent to the reader of the following specification.

In the drawings:

Figure 1 represents a top plan view of the device.

Figure 2 is a side elevational view.

Figure 3 is a front elevational view.

Figure 4 is a fragmentary detailed sectional view taken substantially on a line 4—4 of Figure 2.

Figure 5 is a longitudinal sectional view taken substantially on a line 5—5 of Figure 3 showing the auxiliary stripers removed.

Figure 6 is a fragmentary vertical sectional view through one of the auxiliary stripers.

Figure 7 is a bottom plan view of the structure shown in Figure 2.

Figure 8 is a cross sectional view taken substantially on the line 8—8 of Figure 2.

Figure 9 is a perspective view of the spring guide arm.

Figure 10 is a plan view of a slightly modified form of applicator head.

Referring to the drawings, wherein like numerals designate like parts, it can be seen that the device consists of a main stiper and a pair of auxiliary stripers.

The main stiper consists of an elongated barrel 5 having a rod 6 slidable through the butt end 7 thereof. This rod is equipped with a handle 8 at its outer end and a piston 9 at its inner end and is intended to force paint into the barrel 5 toward a stiper wheel 10 which is mounted within a bifurcated head 11, this head being provided with a reduced skirt 12 snugly projecting into the forward end of the barrel 5. The fit of the wheel 10 in the bifurcated head 11 is very snug and the paint is carried out of the barrel by the peripheral portion of the wheel. Obviously the bi-

furcated head 11 with the wheel 10 can be removed from the barrel 5 when replenishment of paint or changing of the same to another color is desired.

Figure 10 discloses a modified form of applicator head which consists of a bifurcated shell 11a, between the furcations of which is mounted an applicator wheel 10a. At the inner end portion of the bifurcation, the bifurcation opens into an enlarged slot 12a, this slot extending into a reduced skirt portion 12b which is disposed into a barrel, such as the barrel 5 in Figure 5. This slot 12a extends from the shoulder 12c inwardly of the skirt 12b, so that it is normally covered by the shell 5 when in use. However, when the head is removed from the shell 5, dried paint can be easily removed by inserting some implement through the slot 12a.

A boss 13 rises from the barrel 5 and has a threaded bore 14 therein for receiving a screw having a knurled head 15 which can be clamped against the intermediate portion of a rod 16 seated in a groove 17 in the boss 13, this rod 16 having a depending leg 18 which serves as a guide for the stiper while riding along the surface to be striped.

The device is capable of accommodating the auxiliary stripers generally referred to by numerals 19 and 20.

To accommodate these auxiliary stripers, a cross member 21 is utilized, this cross member having a split clamp structure 22 for attaching the member to the forward end of the barrel 5 as in the manner substantially shown in Figure 2. Rising from this cross member 21 are end lugs 23—23, each of which has a threaded opening therein for receiving a pointed screw 24. Each of these screws 24 has a knurled head 25 and interposed between these knurled heads 25 and the lugs 23 are knurled jamb nuts 26.

Rising from the intermediate portion of the cross member 21 is a riser 27 having a horizontal bore for receiving a cross pin 28, the ends of which are pointed, and having a vertical bore for accommodating a set screw 29 which bites into the intermediate portion of the pin 28 to hold the said pin fixed.

Each of the auxiliary stripers 19 and 20 consists of a vertically disposed barrel 30 having a rearwardly extending shank 31 welded thereto. Each of these shanks have depressions in the sides thereof and are interposed between corresponding screws 24 and ends of the cross pin 28 with the pointed ends of these elements disposed into the recesses of the shank as substantially shown

in Figure 4. Thus the barrels 30 are mounted and spring member 32 project rearwardly from the shanks 31 to bear against the rod 16, as shown in Figure 1, to hold the auxiliary stripers against the work.

As disclosed in Figure 4, stabilizing compression springs 31a are interposed between the cross members 21 and the shanks 31.

Bifurcated heads 33 similar in construction to the head 11 are equipped with similar type wheels 33 and disposed into the lower ends of the barrels 30, as substantially shown in Figures 3 and 6.

Elbow sections 34 may be connected to the upper ends of the barrels 30, 30 and horizontally disposed sections 35 provided with caps 36 may be attached to the upper ends of the elbow sections 34, thus elongating the reservoirs of the auxiliary stripers and disposing the same laterally to conserve space and permit more ready handling thereof.

It can now be seen that the paint in the auxiliary stripers is gravity fed while in the barrel 5 the reservoir space can be reduced from time to time by advancing the piston 9 so as to always have a plentiful supply of paint against the stiper wheel 10.

It is preferable that in addition to the guide leg 18, guide means generally referred to by numeral 40 is employed. This guide means 40 consists in the provision of a block 41 welded or otherwise secured to barrel 5 and having machine bolts 42 extending therethrough to screw into threaded bores in a substantially segmental-shaped plate 43. An intermediate portion of this plate 43 is formed with a threaded bore to receive the threaded shank of a winged screw 44, which also passes through an opening at one end of a guide arm 45. The arm 45 is of spring material and has a reduced arcuate-shaped finger portion 46 at its opposite end.

Obviously, this arm 45 can be disposed to any oblique position relative to the longitudinal axis of the barrel 5, for the purpose of riding an automobile body bead or other protuberance or groove that can be utilized in conjunction with the spring arm 45 to guide the stiper.

Furthermore, with the provision of the spring guide arm 45, the stiper can be changed from right to left and from left to right operation with but a slight adjustment of the winged screw 44.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is—

1. A stiper comprising a substantially horizontal reservoir, a stiper element at one end of the reservoir and adapted to receive striping material from the reservoir, a pair of auxiliary stiper units mounted on the reservoir and each provided with a vertically disposed reservoir, and fulcruming means for the auxiliary stripers, and spring means for holding the fulcrumed auxi-

lary stripers against work, a retaining member on the first mentioned reservoir, a rod held on the first-mentioned reservoir by the set screw and provided with a guide leg extending from one end thereof, said spring means projecting from the auxiliary stripers and bearing against the said rod.

2. A stiper comprising a substantially horizontally disposed reservoir having a head portion, said head portion being formed with a vertical slot, a stiper wheel mounted within the slot with a portion of the wheel protruding exteriorly of the head, the edge portions of the head at the slot snugly engaging the wheel to preclude the escape of the contents of the reservoir, said head being slidably connected to the reservoir and having the slot extending a substantial distance longitudinally of the head to permit setting of the head with respect to the reservoir to regulate the amount of the contents of the reservoir to be carried through the slot by the wheel.

3. A stiper comprising an elongated reservoir, a stiper element at one end of the reservoir constructed to carry striping material from the reservoir, and a pair of auxiliary stiper units mounted on the reservoir, each of the units being provided with a vertically disposed reservoir, said element and units being adapted to operate simultaneously on a common plane.

4. A stiper comprising an elongated reservoir, a stiper element at one end of the reservoir constructed to carry striping material from the reservoir, and a pair of auxiliary stiper units mounted on the reservoir, each of the units being provided with a vertically disposed reservoir, said element and units being adapted to operate simultaneously on a common plane, each of the auxiliary reservoirs being provided with a laterally disposed upper portion.

5. A stiper comprising an elongated reservoir, a stiper element at one end of the reservoir constructed to carry striping material from the reservoir, and a pair of auxiliary stiper units mounted on the reservoir, each of the units being provided with a vertically disposed reservoir, said element and units being adapted to operate simultaneously on a common plane, each of the auxiliary reservoirs being provided with a laterally disposed upper portion, one of said laterally disposed upper portions being located above the other and disposed in the same general direction.

6. A stiper comprising a substantially horizontally disposed reservoir having a head portion, said head portion being formed with a vertical slot, a stiper wheel mounted within the slot with a portion of the wheel protruding exteriorly of the head, the edge portions of the head at the slot snugly engaging the wheel to preclude the escape of the contents of the reservoir, said head being adjustable to regulate the amount of material carried by the wheel from the reservoir, and an adjustable spring guide on the bottom of the reservoir.
